UNITED STATES PATENT OFFICE.

JOSEPH DELA MAR, OF NEW YORK, N. Y., ASSIGNOR OF ONE-HALF TO
JACOB J. NICHOLS, OF BROOKLYN, NEW YORK.

PROPELLER FOR MARINE VESSELS.

No. 823,476.

Specification of Letters Patent.

Patented June 12, 1906.

Application filed August 8, 1905. Serial No. 273,245.

To all whom it may concern:

Be it known that I, JOSEPH DELA MAR, a resident of the city of New York, borough of Manhattan, and State of New York, have invented a certain new and useful Improvement 5 in Propellers for Marine Vessels, of which the following is a specification.

My improvement consists in the combination of a set of propeller-blades arranged at 10 suitable intervals and angles on a spirally-formed rib and another set of propeller-blades arranged within the spiral rib of the first-mentioned set, but entirely disconnected.

15 A feature of this improvement consists of means for supporting the two sets of propeller-blades so that they may be rotated at different speeds.

Another feature is a reverse inclination of 20 one set of propeller-blades relatively to the other set and means for rotating the two sets of propeller-blades in opposite directions.

Each set of propeller-blades may be extended helically for any desired length about 25 its axis, as will now be set forth in detail.

In the drawings, Figure 1 is a top view of plan of a propeller embodying my improvement, a certain part being broken away to exhibit another which is contained within it; 30 and Fig. 2 is a transverse section of the same, taken at the plane of the dotted line 2-2 in Fig. 1.

35 A designates a tubular shaft supported in a bearing B and also supported by an internal shaft C. The projecting end of the shaft A has mounted upon it a collar D, and at the projecting end of the shaft C is also a loose collar D', the latter being free to turn independently of the shaft C and to turn with the 40 shaft A.

A spiral rib E is secured at one end to the collar D of shaft A and at the other to the loose collar D', thus securing this shaft and the collar together, so they will rotate in unison. To this spiral rib part is attached a number of obliquely-disposed blades F. As 45 here shown, each of these blades is provided with a lug f', with which is combined a screw f'', passing through it and engaging with a tapped hole in the spiral rib, these blades being secured at regular intervals to the rib. This means of attaching the blades to the rib makes it possible to adjust them at various angles, because the screws when tightened

will clamp the blades in their desired positions upon the rib. 55

The shaft C is shown as supported in bearings G' G''. Between the collars D D' the shaft C has affixed to it a number of propeller-blades H. These may be advantageously secured in the same way as the blades F—namely, by means of lugs h' and screws h'' passing through said lugs and engaging with tapped holes in the shaft C—this mode of securing them being desirable, because it affords opportunity for varying the inclination of the blades. The blades H are of such extension diametrically of the shaft C that they may work within the spiral rib.

To the shaft A is secured a gear-wheel I and to the shaft C a gear-wheel J for the purpose of enabling rotary motion to be transmitted from any suitable source of power to the said shafts independently of one another.

As here shown, both the gear-wheels I J derive motion from a power-shaft K through

the agency of gear-wheels L M, affixed to the latter. The gear-wheel L is shown as engaging directly with the gear-wheel I; but the gear-wheel M is shown as engaging with the 80 gear-wheel J through an intermediate gear-wheel O, supported upon a shaft P. When the shafts A C are thus rotated, they will turn in opposite directions, and this would be proper when the two sets of propeller-blades F and H are arranged in reversely-extending helices. The speeds at which the two sets of blades will rotate may or may not be the same. It is also optional with the constructor to extend the two sets of blades 85 helically to any length about the shafts A C. Inclination of blades in the two sets, the relative speeds of the two sets of blades, and the length of the helices comprising the two sets of blades are all variable at the will of the 90 constructor to meet his requirements from time to time.

Attention is called to the peculiar structural formation of the various parts herein, and particularly to the manner in which the 100 spirally-formed rib E is arranged relative to the direction of rotation. In Fig. 2 the dart R illustrates the direction of motion of the outer set of blades and the dart S the direction of motion of the inner set of blades. The 105 spirally-formed rib E is thus shown to be so arranged that as the propeller-wheel moves forward it moves through the water in the

form of a screw, with the result that it produces but little resistance to the water, and the blades F, which are attached thereto exteriorly, therefore rotate through a mass of water which is not disturbed or agitated by radially-projecting arms. As this type of wheel is designed to rotate at a high rate of speed, it is obvious that the tendency of the blades F is to throw the water outwardly from the shaft, and thus form a core within the rib of less density than without. To counteract this tendency, the inner blades H are secured to the shaft C at reverse inclinations to the blades F, so that the inner and outer blades rotate in opposite directions, and preferably the inner blades travel at a higher speed than the outer blades, the result being that the inner blades have a tendency to produce a vacuum, and the mass of water surrounding the wheel is thus impelled to move toward the core of the wheel, making possible a more effective action of the blades than would otherwise be the case.

It is obvious that my structure permits of most efficient working when the wheel is reversed, and, furthermore, the cost of construction is not prohibitive for this class of wheels.

What I claim as new is—

1. The combination of a set of propeller-blades on a spirally-formed rib, and another set of propeller-blades arranged within the annulus of the first-mentioned set, substantially as described.

2. The combination of a set of propeller-blades, on a spirally-formed rib, and another set of propeller-blades arranged within the annulus of the first-mentioned set, one of said sets of blades being adjustably fastened to its supports, substantially as described.

3. The combination of a set of propeller-blades on a spirally-formed rib, and another set of propeller-blades arranged within the annulus of the first-mentioned set, both of said sets of blades being adjustably fastened to their supports, substantially as described.

4. The combination of a set of propeller-blades on a spirally-formed rib, and another set of propeller-blades reversely inclined to and arranged within the annulus of the first-mentioned set, substantially as described.

5. The combination of a set of propeller-

blades on a spirally-formed rib, another set of propeller-blades arranged within the annulus of the first-mentioned set, and means for rotating the two sets of propeller-blades at different rates of speed, substantially as described.

6. The combination of a set of propeller-blades on a spirally-formed rib, another set of propeller-blades reversely inclined to and arranged within the annulus of the first-mentioned set, and means for rotating the two sets of blades in opposite directions, substantially as described.

7. A propeller-wheel, comprising the combination of a tubular shaft having on its projecting end a rigid collar, an internal shaft through the tubular shaft and projecting beyond, provided with loose collar, a spiral rib secured at its opposite ends to the rigid collar on the tubular shaft, and to the loose collar on the internal shaft, a set of propeller-blades mounted on the spiral rib and a set of propeller-blades mounted on the internal shaft within said spiral rib, as set forth.

8. A propeller-wheel having a spiral rib secured to a tubular shaft and so arranged that the wheel in moving through the water will follow the motion of a screw, propeller-blades exteriorly on said rib, and propeller-blades within said rib, secured to an independent shaft, and disconnected from said rib.

9. A propeller-wheel having a series of adjustable propeller-blades arranged at regular intervals along a spirally-formed rib, and a series of adjustable propeller-blades on a shaft within said rib and operating independently of said outer blades.

10. A propeller-wheel having a series of adjustable propeller-blades arranged at intervals along a spirally-formed rib, and a series of adjustable propeller-blades on a shaft within said rib and rotating in a direction opposite to the blades on the rib.

In testimony whereof I have signed this specification in the presence of two subscribing witnesses.

JOSEPH DELA MAR.
